(74) *Attorney, Agent, or Firm* — TMB Law; Timothy M. Brown

(57) **CLAIM**

The ornamental design for a pop-up camper for pick-up truck, as shown and described.

DESCRIPTION

1. Pop-up camper for pick-up truck

1.1 is a top, rear, and left side perspective view of a pop-up camper for pick-up truck embodying my new design as installed on an exemplary vehicle;

1.2 is a top, rear, and left side perspective view of the pop-up camper for pick-up truck as a standalone unit;

1.3 is a right side elevation view thereof;

1.4 is a left side elevation view thereof;

1.5 is a front elevation view thereof;

1.6 is a rear elevation view thereof;

1.7 is a top plan view thereof;

1.8 is a bottom plan view thereof;

1.9 is a top, rear, and left side perspective view of the pop-up camper for pick-up truck in a raised configuration and as installed an exemplary vehicle;

1.10 is a top, rear, and left side perspective view of the pop-up camper for pick-up truck as a standalone unit in a raised configuration;

1.11 is a left side elevation view thereof;

1.12 is a right side elevation view thereof;

1.13 is a front elevation view thereof;

1.14 is a rear elevation view thereof;

1.15 is a top plan view thereof;

1.16 is a bottom plan view thereof;

1.17 is a top, rear, and left side perspective view of the pop-up camper for pick-up truck in a raised and opened configuration and as installed an exemplary vehicle;

1.18 is a top, rear, and left side perspective view of the pop-up camper for pick-up truck as a standalone unit in a raised configuration;

1.19 is a left side elevation view thereof;

1.20 is a right side elevation view thereof;

1.21 is a rear elevation view thereof;

1.22 is a front elevation view thereof;

(Continued)

1.23 is a top plan view thereof; and
1.24 is a bottom plan view thereof.

The parts shown in broken lines in the reproductions are not part of the claimed design; reproductions 1.1 to 1.8 show the pop-up camper for pick-up truck in a closed state; reproductions 1.9 to 1.16 show the pop-up camper for pick-up truck in a first open state; reproductions 1.17 to 1.24 show the pop-up camper in a second open state.
